UNITED STATES PATENT OFFICE.

CHARLES E. HARTHAN, OF LYNN, MASSACHUSETTS, ASSIGNOR TO THE
GENERAL ELECTRIC COMPANY, OF NEW YORK.

DESIGN FOR A CYLINDER-CAP FOR ARC-LAMPS.

SPECIFICATION forming part of Design No. 29,632, dated November 8, 1898.

Application filed April 23, 1898. Serial No. 678,674. Term of patent 14 years.

To all whom it may concern:

Be it known that I, CHARLES E. HARTHAN, a citizen of the United States, residing at Lynn, in the county of Essex, State of Massachusetts, 5 have invented and produced a new and original Design for Cylinder-Caps for Inclosed-Arc Lamps, (Case No. 809,) of which the following is a specification.

In the accompanying drawings, which illustrate my invention, Figure 1 is a perspective view of a cap intended for use on the cylinder of an inclosed-arc lamp. Fig. 2 is a section thereof.

The leading feature of the design consists 15 in the configuration of the cap, consisting, as shown in the drawings, of a pair of disks or flanges of different size, which are united by a central body or hub, with a central opening through the hub and disks. The cap consists 20 of a pair of comparatively thin flat disks or

flanges A and B, which differ slightly in their diameters, that of the upper disk A being somewhat greater than that of the disk B. The two disks are united by a central body or hub C, which is provided with a central opening D to receive the carbon. Extending circumferentially in the hub are small chambers E, which communicate with the central opening D. 25

What I claim is—

The design for a cylinder - cap of an inclosed-arc lamp, substantially as shown and described.

In witness whereof I have hereunto set my hand this 20th day of April, 1898.

CHARLES E. HARTHAN.
